Inventor

Isaac R. Potter

UNITED STATES PATENT OFFICE.

ISAAC R. POTTER, OF DARTMOUTH, MASSACHUSETTS.

IMPROVEMENT IN HORSESHOES.

Specification forming part of Letters Patent No. **80,213**, dated July 21, 1868.

To all whom it may concern:

Be it known that I, ISAAC R. POTTER, of Dartmouth, in the county of Bristol, in the State of Massachusetts, have invented a new and Improved Horseshoe; and I do hereby declare that the following is a full and exact description thereof, reference being had to the accompanying drawings, and to the letters of reference marked thereon.

My invention consists in forming metallic shoes with raised edges and studs, and with movable calks, made in such manner that, when applied, the bearing-edge will be flush with the wall of the hoof, and in making the calks whole or in parts, with the edge continuous or indented.

Figure 1 is a perspective view of the shoe complete. Fig. 2 is a view of the shoe with one calk removed. Fig. 3 is a view of calk removed from shoe.

Fig. 1: A¹ is the shoe; B¹B¹, calks; C¹C¹C¹, rib on inner edge of shoe to steady the calks; D¹D¹D¹D¹, screw-bolts for securing calks to shoe.

Fig. 2: A² is the shoe; B², calk; C²C²C²C, rib on inner edge of shoe; D²D², bolts; E²E², studs, in which the bolts are screwed; a²a²a²a², nail-holes.

Fig. 3: B³, calk inverted, showing apertures for bolts to pass through, countersunk to fit studs E²E², (see Fig. 2;) D³, bolt.

The flanges of the calks B B, when con-

structed in separate parts, should be curved at the heel and toe, as shown, or, when continuous, at the heel only.

The shoe being constructed, in the manner herein described, with raised edges and studs, and the shoe secured to the hoof in the usual manner, the calks are secured to the shoe with bolts, as shown, and will be prevented from slipping by the raised edges and studs, which will also prevent the bolts from jarring loose. The raised edge may be broken, as shown, or continuous.

In this invention I do not claim any device previously invented or patented for horseshoe; but

What I claim as my invention, and desire to secure by Letters Patent, is—

1. The shoe A, as described, with raised edge C and studs E².

2. The removable calks B¹B¹, made in sections or continuous, with edge continuous or indented.

3. Forming and applying the calks so that the bearing-edge will be flush with the wall of the hoof.

4. Curving the calks at the heel and toe, as shown.

ISAAC R. POTTER.
